UNITED STATES PATENT OFFICE.

JOHN SCHARL, OF NEW YORK, N. Y.

DESIGN FOR A PENCIL-TIP.

44,818.

Specification for Design.

Patented Oct. 28, 1913.

Application filed August 28, 1912. Serial No. 717,613. Term of patent 14 years.

To all whom it may concern:

Be it known that I, JOHN SCHARL, a citizen of the United States, residing at New York, in the county of New York and State of New York, have invented a new, original, and ornamental Design for Pencil-Tips, of which the following is a specification, reference being had to the accompanying drawing, forming a part thereof.

Figure 1 is a side elevation of a pencil

tip showing my new design. Fig. 2 is a front elevation of the same.

I claim:

The ornamental design for a pencil tip, as shown.

JOHN SCHARL.

Witnesses:

JOHN W. DONEGHEY,
C. JAMES CRONIN.
